[57] CLAIM

The ornamental design for a picnic table, as shown and described.

DESCRIPTION

FIG. 1 is a perspective view of a picnic table showing my new design;

FIG. 2 is an end elevational view thereof, the opposite end being of substantially the same appearance;

FIG. 3 is a side elevational view thereof, the opposite side being of substantially the same appearance; and

FIG. 4 is a top plan view thereof.
